[57] CLAIM

The ornamental design for a triangular shaped pool cue shaft, as shown and described.

DESCRIPTION

FIG. 1 is a perspective view of a triangular shaped pool cue shaft showing my new design;

FIG. 2 is a rear elevational view thereof;

FIG. 3 is a right side elevational view thereof;

FIG. 4 is a left side elevational view thereof;

FIG. 5 is a front elevational view thereof;

FIG. 6 is a perspective view of a second embodiment of FIG. 1;

FIG. 7 is a rear elevational view thereof;

FIG. 8 is a right side elevational view thereof;

FIG. 9 is a left side elevational view thereof;

FIG. 10 is a front elevational view thereof;

FIG. 11 is a perspective view of a third embodiment of FIG. 1;

FIG. 12 is a rear elevational view thereof;

FIG. 13 is a right side elevational view thereof;

FIG. 14 is a left side elevational view thereof; and,

FIG. 15 is a front elevational view thereof.

The broken lines shown are for illustrative purposes only and form no part of the claimed invention.
